AIR CONDITIONING SYSTEM

William L. McGrath, St. Paul, Minn., assignor to
 Minneapolis-Honeywell Regulator Company,
 Minneapolis, Minn., a corporation of Delaware

Application May 14, 1938, Serial No. 208,088

7 Claims. (Cl. 62-6)

This invention relates to an air conditioning system and more particularly to a system wherein sensible and latent heat is removed from air which is circulated through a space according to the requirements of the space.

In accordance with my invention air is circulated over a pair of evaporator coils of a refrigeration system, the air then being circulated through the room or space to be conditioned. A compressor running at constant speed supplies refrigerant to the evaporator coils and the flow of refrigerant to each of the coils is controlled by suitable valve means. When the temperature of the space is above a desired value and the humidity is at or below a desired value, refrigerant is supplied to both of the evaporator coils. Should the humidity rise to an undesirable value, the flow of refrigerant to one of the evaporator coils is interrupted with the result that the temperature of the other evaporator coil will be lower than the temperature of the coils when refrigerant is flowing through both of the coils. This is desirable since less heat must be removed from the air in order to effect a reduction in temperature of the air than is necessary when dehumidification is required, since in order to reduce the temperature it is necessary only to remove sensible heat from the air whereas when dehumidification is required, both sensible and latent heat must be removed from the air. The coils are so arranged that a portion of the air passes over one coil and another portion of the air passes over the other coil so that when one coil only is being utilized for dehumidification some of the air passing through the chamber will by-pass this coil and may be utilized for reheating the air. Means are also provided for supplying refrigerant to both of the coils should the temperature in the space become excessively high regardless of the humidity in the space in order that a maximum amount of sensible cooling may take place.

It is therefore an object of my invention to provide a novel control means for the evaporator coils of a refrigeration system wherein these coils are used to control the temperature and humidity conditions within a space to be conditioned.

Other objects will become apparent upon a study of the specification, claims, and appended drawing, the single figure of which illustrates diagrammatically one form of my invention.

Referring more particularly to the drawing, an air conditioning chamber is represented by the reference character 10. This chamber may include a fresh air inlet 11, a return air inlet 12, an outlet 13, and a fan 14 driven by a motor

15 for circulating air through the chamber 10 and a space 16 to be conditioned. Dampers 17 and 18 may be provided in the fresh and return air inlets, respectively, for controlling the proportions of fresh and return air admitted to the chamber 10. These dampers may be manually operated or automatically operated in any suitable manner.

Mounted within the chamber 10 and transversely arranged with respect to one another are 10 a pair of evaporators 20 and 21. A compressor 22 driven by a motor 23 is provided for supplying refrigerant to the evaporator coils 20 and 21. The high pressure side of the compressor 22 is 15 connected by means of a pipe 26 with a condenser 27. A pipe 28 connected to the outlet of the condenser 27 leads the refrigerant to a pair of valves 30 and 31. The outlet of valve 30 communicates with the inlet of the evaporator 20 by means of a pipe 33 and a second pipe 34 leads 20 refrigerant from the outlet of valve 31 to the inlet of evaporator 21. The flow of refrigerant into the evaporators 20 and 21 is also controlled by suitable expansion valves 36 and 37, respectively, these valves being of any conventional construction. Pipes 40 and 41 are connected to the outlets of evaporators 20 and 21, respectively, and communicate with a pipe 42 leading to the inlet of the compressor 22. In the operation 30 of the refrigerating apparatus the refrigerant is compressed by the compressor 22, is condensed by the condenser 27, and then flows into the coils 20 and 21 providing the valves 30 and 31 are open, where the refrigerant is evaporated, the 35 flow of refrigerant into the evaporators also being controlled by the expansion valves, the refrigerant being evaporated in the evaporators and absorbing heat from the air passing thereover and the evaporated refrigerant then flowing back 40 to the compressor 22.

For controlling the operation of the compressor I have illustrated a suction pressure controller 45. This controller may include an expandible bellows 46 connected by means of a pipe 47 to the pipe 42 leading to the inlet of the compressor. A lever 48 pivoted at 49 is biased by means of a spring 50 into engagement with the upper portion of the bellows. Lever 48 carries a mercury switch 52 of conventional construction 50 and when the pressure on the suction side of the compressor drops to a low enough value, the bellows 46 contracts and a lever 48 is moved under the influence of spring 50 to a position in which the circuit through the switch 52 is interrupted. Line wires 53 and 54 may be connected to a suit-

able source of power (not shown) and are provided for supplying energy to the motor 23 as well as to the positioning means for the valves 30 and 31 as will be henceforth explained. Power is supplied to the motor 23 when the suction pressure on the suction side of the compressor is above a predetermined low value through the following circuit: from the line wire 53 through conductors 56, mercury switch 52, conductor 57, motor 23, and conductor 58 to the line 54. It will now be clear that when the suction pressure drops to a low enough value this circuit to the motor 23 will be interrupted by the contraction of the bellows 46.

The positions of valves 30 and 31 may be controlled by suitable means 60 and 61 which may be in the form of solenoids having an armature suitably connected to the valves. Energization of the solenoids causes the valves to be moved to open positions and upon deenergization of the solenoids the valves may be moved to closed positions under the influence of gravity or a suitable biasing means (not shown).

Mounted within the space to be conditioned is a thermostat indicated generally by the reference character 64. This thermostat may include a bimetallic element 65 and an arm 66 carried thereby and engaging a resistance 67 across which the arm 66 sweeps in response to variations in temperature in the space 16, the arm moving to the right in response to an increase in temperature and to the left upon a decrease in temperature. The arm 66 and resistance 67 form a control potentiometer for a motor 68. This motor may be a proportioning motor of the type illustrated in Patent No. 2,028,110 issued to D. G. Taylor on January 14, 1936. The terminals 69 and 70 of the motor are connected to the extremities of resistance 67 by means of conductors 71 and 72, respectively. The terminal 76 is connected to the arm 66 of the thermostat 64 by means of conductors 73, 74 and the center tapped resistance 75. Power is supplied to the motor by means of wires 78 and 79 connected to a suitable source of power (not shown). It will be understood upon a study of the above mentioned Taylor patent that as the arm 66 moves across the potentiometer 67, the shaft 80 driven by the motor 68 will rotate an amount which is proportional to the extent of movement of the arm 66 with the resistance 67.

Also connected to the center terminals 76 of the motor 68 by means of conductors 73, 82, adjustable resistance 83, and conductor 84 is the control arm 85 of a second potentiometer. The arm 85 forms one arm of a bell crank lever pivoted at 86, the other arm 87 thereof being biased by means of spring 88 with the upper portion of the bellows 89. The bellows 89 is connected by means of a capillary tube 90 to a bulb 91, the tube, bulb, and bellows being filled with a suitable volatile fluid. The bulb 91 may be positioned outdoors so that the bellows 89 will expand and contract in response to variations in outdoor temperature. It will be apparent that as the bellows expands and contracts the arm 85 will be caused to move over the resistance 84. Upon an increase in outdoor temperature the arm 85 will move to the right and upon a decrease in outdoor temperature the arm 85 will move to the left over the resistance 84. The right end of resistance 84 is connected by means of conductors 96 and 71 with the terminal 69 of the motor 68 and the opposite end of the resistance 84 is connected by means of conductors 75

97 and 72 with the motor terminal 70. It will now be seen that the potentiometers 84 and 67 are connected in parallel to the motor 68 and accordingly movement of either arm 85 or 66 with respect to the corresponding resistances will cause movement of the shaft 80 of the motor 68. By reason of the adjustable resistance 83 interposed in the circuit to the arm 85 this arm will have less effect on the motor for a given movement thereof than will the arm 66. In other words, in order to cause the shaft 80 to move from one extreme position to the other the arm 85 may have to move from one end of the resistance 84 to the other whereas in order to give a corresponding movement to the motor the arm 66 will have to move only through the distance X. Accordingly a movement of the arm 85 with respect to resistance 84 has the effect of shifting the control range of the arm 66 with respect to the resistance 67 so that as the arm 66 moves to the right for example in response to an increase in outdoor temperature the arm 66 will have to move to the right in order to cause the motor to return to its initial position so that the control range of the arm 66 will move to the right in response to a movement of the arm 85 to the right and likewise upon movement of the arm 85 to the left the control range of the arm 66 will be shifted to the left. The provision of the center tapped resistance insures that the control range X of the arm 66 will have the same magnitude regardless of the position of this control range.

Carried by the shaft 80 are a pair of cams 100 and 101. Operated by the cam 100 is a switch arm 102 which engages a fixed contact 103 upon movement of the cam to a position wherein the arm 102 is moved upwardly. Likewise the cam 101 operates a switch arm 104 which cooperates with a fixed contact 105. These cams are so arranged that as the cams rotate in a clockwise direction arm 102 will first be moved into engagement with the contact 103 and subsequently the arm 104 will be moved into engagement with the contact 105. As the arm 66 moves towards the right the cams 100 and 101 are rotated in a clockwise direction by the motor 68 through an amount which is proportional to this arm. As the arm 66 moves toward the right in response to an increase in the temperature of the space the arm 102 will first be moved by the cam 100 into engagement with the switch contact 103 and upon further movement of the arm 66 to the right the arm 104 will be moved into engagement with the fixed contact 105. The temperatures at which the arms engage their respective contacts will depend upon the position of the control range X of the arm 66 of thermostat 64 and since this in turn depends upon the outdoor temperature it will be seen that as the outdoor temperature rises the temperature at which the arms engage their respective contacts will be correspondingly higher.

Also mounted within the space 16 is a humidity responsive device 110 which may be of any suitable construction and is shown as comprising a humidity responsive element 111 fixed at one end as at 112 and having its opposite end connected to a lever 113 pivoted at 114 and biased upwardly by means of a spring 115. Carried by the lever 113 is a mercury switch 120, this switch including contacts 121, 122, 123, and 124 and a mercury element 125. When the humidity is low the switch will be tilted in the position illustrated and

contacts 123 and 124 will be connected by the mercury element 125. Upon an increase in relative humidity the element 111 will expand and lever 113 will be moved upwardly under the influence of the spring 115 until the contacts 121 and 122 are connected by the mercury element 125.

When the arms 102 and 104 are in the positions illustrated and the switch 120 operated by the humidity responsive device 110 is in the position illustrated, the solenoids 60 and 61 are deenergized and valves 30 and 31 are both closed thus preventing flow of refrigerant to either evaporator coil, so that the air being circulated through the chamber 10 is not cooled thereby. Should now the temperature in the space increase to a high enough value, the arm 102 will be moved by cam 100 into engagement with contact 103 since the movement of arm 66 of thermostat 64 to the right in response to an increase in temperature will cause shaft 60 to rotate the cam 100 in a clockwise direction. The solenoids 60 and 61 will now be energized as follows, it being assumed that the humidity in the space has not risen to a sufficiently high value to tilt the switch 120 in the opposite direction. Current flows through the solenoid 60 as follows: from line 53 through conductor 130, contact 103, switch arm 102, conductor 131, contacts 123 and 124 of switch 120, conductors 134, 135 to the solenoid 60 and conductors 136 and 137 to the line 54. Current flows through the solenoid 61 as follows: from line 53 through conductor 130, contact 103, switch arm 102, conductor 138, solenoid 61, and conductors 139 and 137 to the line 54. Thus upon a rise in temperature to a certain value both valves 30 and 31 are open providing the humidity in the space is relatively low so that refrigerant is now supplied under the control of the expansion valves 36 and 37 to the evaporators 20 and 21 whereby a reduction in temperature of the air passing through the chamber 10 is effected.

Assume now that the temperature is high and that the humidity in the space reaches an undesirable value and that switch 120 is tilted in the opposite direction wherein the circuit through contacts 123 and 124 are broken and contacts 121 and 122 are bridged by the mercury element 125. If the temperature in the space has not risen to such a high value that arm 104 has moved into engagement with contact 105, the aforescribed circuit to the solenoid 60 is interrupted and this solenoid is therefore deenergized thus causing the valve 30 to be closed. Refrigerant now flows only through the evaporator coil 21 thus causing a reduction in the suction pressure in the refrigeration system and therefore a reduction in temperature of the coil 21. The greater proportion of the heat that is removed from the air is now in the form of latent heat so that the temperature and humidity in the space are both reduced. Some of the air passing through the chamber 10 will of course pass over the coil 20 and will not come into contact with the coil 21 so that only a relatively small proportion of the air is cooled by the evaporators and the air by-passing the coil 21 may be utilized to reheat the air which is cooled and dehumidified by the coil 21.

Should now the temperature of the air increase to an excessive degree while the humidity in the space is relatively high, the arm 104 will be moved by the cam 101 into engagement with the contact 105 thus again energizing the solenoid 60 through the following circuit: from the line wire 53 through conductors 130, 139, 151, contact 105,

5 arm 104, conductor 135, solenoid 60, and conductors 136 and 137 to the line wire 54. Both solenoids are now energized so that refrigerant is again supplied to both the evaporators 20 and 21 and more sensible cooling in proportion to latent cooling of the air is effected so that the temperature of the air will more rapidly be reduced to the desired value.

10 Assume now that the temperature of the air is at a desirable value so that both switch arms 102 and 104 are out of engagement with their respective contacts but the humidity of the air rises to an excessive value so that contacts 121 and 122 of the switch 120 are bridged by the mercury element 125. Current now flows through the solenoid 61 as follows: the line wire 53 through conductors 130, 150, 155, contacts 121 and 122 of the switch 120, conductors 131, 138, solenoid 61, and conductors 139 and 137 to the line wire 54. The 15 evaporator coil 21 is now available for dehumidification of the air although no sensible cooling is at the time required.

20 When coil 21 is being used for dehumidification the temperature of the air leaving the outlet 13 may be so low as to reduce the temperature of the air within the space 16 below a desirable value. A coil 160 is accordingly placed downstream from the evaporators 20 and 21 and a suitable heating medium is supplied to this coil under the control of valve 161. The stem 162 of the valve 161 may be connected by means of a link 163 to the arm 164 operated by a motor 165 which may be a proportioning motor similar to the motor 68. The operation of this motor is controlled by a thermostat 170 located in the space 16. This thermostat may be similar in construction to the thermostat 64 and may include bimetallic element 171 carrying an arm 172 for movement therewith over resistance 173, the arm 172 and resistance 173 forming the control potentiometer for the motor 165. Terminals 174 and 175 of the motor are connected by means of conductors 176 and 177 to the opposite ends of the resistance 173 and the terminal 178 is connected by means of conductor 179 to the arm 172 through the bimetallic element 171. Wires 180 and 181 are provided to supply power to the motor 165. When the temperature of the air is at a high enough value the arm 172 of the thermostat 170 will be at the extreme right end of resistance 173, and the valve 161 will be closed by the motor 165. Should the temperature in the space 16 fall below a desired value, arm 172 will move toward the right over the resistance 173 thus causing operation of the motor 165 and opening of the valve 161 an amount proportional to the reduction in temperature below the desired value. In this manner whenever the temperature of the air is lowered below the desired value in order to dehumidify the air or for any other reason, the temperature of the air will be again raised by means of the coil 160 to the proper value.

25 It will now be seen that with my system that when the humidity of the air is sufficiently low and when the temperature is higher than desirable, refrigerant is supplied to both evaporators 20 and 21. Should the humidity become excessive, only one evaporator is used and the temperature in that evaporator is accordingly reduced so that dehumidification of the air as well as sensible cooling will take place. Upon excessive temperature conditions refrigerant will be supplied to both coils regardless of the humidity in the space in order to secure maximum

cooling of the air. Also in case the humidity is high and the temperature is at the proper value, refrigerant will be supplied to one of the coils in order to secure dehumidification and the air, if necessary, will be reheated by means of the coil 160. The temperature which will be maintained in the space will be compensated by the controller 89 which responds to the outside temperature so that as the outdoor temperature rises a higher indoor temperature will be maintained in order to secure proper conditions of comfort within the space. If desired however this outdoor temperature compensator may be omitted should it be desirable to maintain the same conditions within the space at all times regardless of the outdoor temperature. The compressor 22 will be controlled by the suction pressure and will continue to operate as long as the suction pressure is above a predetermined value.

Having described the preferred form of my invention, many modifications may become apparent to those skilled in the art and it should therefore be understood that my invention is limited only by the scope of the appended claims.

I claim as my invention:

1. In an air conditioning system, a refrigeration system including evaporator means for removing sensible and latent heat from the air to be conditioned, means for causing a flow of refrigerant through said evaporator means, means for circulating air past said evaporator means and through a space to be conditioned, flow control means for selectively controlling flow of refrigerant through a portion of or through all of said evaporator means or preventing flow of refrigerant through any of said evaporator means, and means in control of said flow control means, said last named means comprising means responsive to the temperature and humidity of said space for controlling said flow control means in a manner to prevent flow of refrigerant to said evaporator means when the space temperature and space humidity are both low, for permitting flow of refrigerant through all of said evaporator means when the space temperature increases to a first predetermined value and the space humidity is low, for permitting flow of refrigerant through a portion only of said evaporator means whenever the space humidity rises to a predetermined value when said space temperature is between said predetermined value and a higher value, and for permitting flow of refrigerant to all of said evaporator means regardless of space humidity when the space temperature rises to said higher predetermined value.

2. In an air conditioning system, a refrigeration system including compressor means and a pair of evaporators for removing sensible and latent heat from air to be conditioned, means for circulating air past said evaporators to a space to be conditioned, a first valve for controlling the flow of refrigerant into one evaporator, a second valve for controlling the flow of refrigerant into the other evaporator, and temperature and humidity responsive means for controlling said first and second valves in a manner to open both valves when space temperature is at an intermediate value and humidity is low, to open only one valve when space temperature is at said intermediate value and humidity is high, and to open both valves regardless of humidity when space temperature rises to a high value.

3. In an air conditioning system, a refrigeration system including compressor means and a pair of evaporators for removing sensible and

latent heat from air to be conditioned, means for circulating air past said evaporators to a space to be conditioned, a first valve for controlling the flow of refrigerant into one evaporator, a second valve for controlling the flow of refrigerant into the other evaporator, and temperature and humidity responsive means for controlling said first and second valves in a manner to close both valves when space temperature and humidity are at low values, to open both valves when space temperature is at an intermediate value and humidity is low, to open only one valve when space temperature is at said intermediate value and humidity is high, and to open both valves regardless of humidity when space temperature rises to a high value.

4. In an air conditioning system, a refrigeration system including compressor means and a pair of evaporators for removing sensible and latent heat from air to be conditioned, means for circulating air past said evaporators to a space to be conditioned, a first valve for controlling the flow of refrigerant into one evaporator, a second valve for controlling the flow of refrigerant into the other evaporator, temperature and humidity responsive means for controlling said first and second valves in a manner to close both valves when space temperature and humidity are at low values, to open both valves when space temperature is at an intermediate value and humidity is low, to open only one valve when space temperature is at an intermediate value and humidity is high, and to open both valves regardless of humidity when space temperature rises to a high value.

5. In an air conditioning system, a refrigeration system including compressor means and a pair of evaporators for removing sensible and latent heat from air to be conditioned, a first valve for controlling the flow of refrigerant into one evaporator, a second valve for controlling the flow of refrigerant into the other evaporator, means for circulating air past said evaporators to a space to be conditioned, first and second switches actuated in sequence upon rising temperature, a humidity actuated switch, and electrical connections between said switches and said valves for placing said switches in control of the same, said electrical connections forming a first circuit means controlled by said first temperature actuated switch and said humidity actuated switch for opening both of said valves, and a second circuit means controlled by said first and second temperature actuated switches for causing opening of both of said valves independently of said humidity actuated switch.

6. An air conditioning system comprising in combination, a pair of evaporators for removing latent and sensible heat from said air, compressor means for supplying said evaporators with refrigerant, each of said evaporators having a constant superheat expansion valve at the inlet thereof, a first valve controlling the flow of refrigerant into one of said evaporators, a second valve controlling the flow of refrigerant into the other of said evaporators, control means for said first and second valves, and temperature and humidity responsive means for actuating said control means to open both of said valves when the temperature rises to a first value and said

humidity is low, to close one of said valves when said humidity is high as long as the temperature is below a second value higher than said first value, and to reopen said one valve regardless of humidity when the temperature reaches said second value.

7. An air conditioning system comprising in combination, a pair of evaporators for removing latent and sensible heat from said air, compressor means for supplying said evaporators with refrigerant, each of said evaporators having a constant superheat expansion valve at the inlet thereof, a first valve controlling the flow of refrigerant into one of said evaporators, a second

5 valve controlling the flow of refrigerant into the other of said evaporators, control means for said first and second valves, and temperature and humidity responsive means for actuating said control means to open one of said valves when the humidity reaches a high value, and to open both of said valves when the temperature rises to a first value and said humidity is low, to close one of said valves when said humidity is high as long as the temperature is below a second value higher than said first value, and to reopen said one valve regardless of humidity when the temperature reaches said second value.

WILLIAM L. McGRATH.
